(57) **CLAIM**

The ornamental design for an orthodontic elastomeric ligature, as shown and described.

DESCRIPTION

FIG. 1 is a front perspective view of an orthodontic elastomeric ligature showing my new design.

FIG. 2 is a top plan view thereof, with the bottom plan view being the same as FIG. 2.

FIG. 3 is a front elevational view thereof, with the rear elevational view being a mirror image of FIG. 3.

FIG. 4 is a left side elevational view thereof; and,

FIG. 5 is a right side elevational view thereof.
